described without in the least departing from the nature and principle of my invention.

Having thus described the invention, what is claimed as new and desired to be secured by Letters Patent is:

1. In a machine of the character described, the combination of the following elements, a rigid support for a grinding surface, a rod arranged adjacent each end of said support, said support being pivotally mounted on said rods, and independently operable adjusting means for bodily shifting said rods, whereby when the rod at one end of the support is being shifted by the means coöperating therewith the other rod serves as a fulcrum about which the support moves; substantially as described.

2. A machine of the character described provided with a rigid support for a grinding surface, a member on which the forward end of said support is pivotally mounted, means for bodily shifting said member, a pivotal support for the rear or inner end of said grinding surface support, and independent means for bodily shifting said rear pivotal support; substantially as described.

3. In a machine of the character described, the combination with a support for a rigid grinding surface, links connected to the inner end of said support, a pair of levers connected to said links, the free ends of said levers being bent toward each other, a single swivel block to which the free ends of said levers are connected, a nut arranged on said swivel block, a hand wheel on said nut, and a

threaded rod for engaging said nut and pivotally connected at its lower end to a stationary support; substantially as described.

4. In a machine of the character described, the combination with a rigid support for a grinding surface, horizontally movable blocks upon which the forward end of said support is pivotally mounted, threaded rods connected to said blocks, nuts on said threaded rods, gears connected to said nuts, and a shaft provided with worms that mesh with said gears so as to rotate them in unison simultaneously and uniformly move said blocks, a pivotal support for the opposite end of said grinding surface, and independent means for bodily shifting said support; substantially as described.

5. In a machine of the character described, the combination with a dead plate and a stationarily mounted grinding surface, of means for adjusting said dead plate and grinding surface horizontally, a rigid grinding surface having two pivotal supports at opposite ends thereof, and means for bodily shifting said pivotal supports at angles to each other, whereby said rigid grinding surface may be adjusted vertically or horizontally or obliquely; substantially as described.

In testimony whereof I hereunto affix my signature in the presence of two witnesses, this twelfth day of March 1907.

MILTON F. WILLIAMS.
